SHOE POLISHING KIT

Henry J. Simeone, New Haven, Conn.

Application October 16, 1958, Serial No. 53,007

Term of patent 14 years

(Cl. D9—2)

Fig. 2

Fig. 3

Fig. 4

Fig. 6

Fig. 5

Fig. 1

Fig. 1 is a perspective view on a reduced scale of a shoe polishing kit embodying my new design.

Fig. 2 is a side elevational view of the shoe polishing kit.

Fig. 3 is an elevational view thereof as seen from the right of Fig. 2.

Fig. 4 is a top plan view of the kit.

Fig. 5 is a bottom plan view thereof.

Fig. 6 is an elevational view thereof as seen from the left of Fig. 2.

I claim:

The ornamental design for a shoe polishing kit, as shown.
